DESIGN FOR SAFETY PAPER

Raymond L. Cote, Los Angeles, Calif., assignor to
The Union Lithograph Co., Inc., Los Angeles,
Calif., a corporation of California

Application October 30, 1933. Serial No. 49,607

Term of patent 14 years

To all whom it may concern:

Be it known that I, RAYMOND L. COTE, a citizen of the United States, residing at Los Angeles, in the county of Los Angeles, State of California, have invented a certain new, original, and ornamental Design for Safety Paper, of which the following is a specification, reference being had to the accompanying drawing.

The figure of the drawing is a plan view of a piece of safety paper embodying my design.

I claim:

The ornamental design for safety paper, as shown.

RAYMOND L. COTE.
